SPINNING RING

Alvin Lodge, Detroit, Mich., assignor to American Viscose Corporation, Wilmington, Del., a corporation of Delaware

Application February 22, 1944, Serial No. 523,391

15 Claims. (Cl. 57—119)

This invention relates to an improved spinning ring for a ring spinning frame for use in the spinning and twisting of yarn, thread, cord, or the like. In spinning and twisting by the usual ring and traveler system, the yarn, thread or the like is fed from a suitable source or supply, such as a package, a drafting device, or artificial fiber spinning machine through a ring in the rail of a spinning machine onto a take-up package, such as a bobbin, spool, or cone, which is mounted on a spindle rotated at high speed. The spinning ring carries a traveler which bears frictionally on the ring and through which the yarn passes as it is wound on the take-up package.

It is the general object of the present invention to provide an improved spinning ring for use in connection with a rotating take-up package which will facilitate and speed up lacing-up of the device, and which will permit of lacing-up the device, if desired, without the necessity of stopping the rotation of the spindle carrying the take-up package.

Essentially my invention contemplates the provision of a combination of means consisting of a resilient split spinning ring, and means for optionally varying the distance between the ends of the ring, to provide a gap in the periphery thereof, or to form a substantially continuous closed circle, as desired.

In the drawing illustrative of the invention,

Figure 1 is a fragmentary top view of a ring rail of a spinning or twisting frame equipped with a plurality of spinning rings according to my invention;

Figure 2 is a front elevation of my improved spinning ring and closing and opening means therefor, the rail being sectioned on line II—II of Figure 1;

Figure 3 is a modification of the ring shown in Figure 2;

Figure 4 is a fragmentary plan view of the arrangement shown in Figure 3; and

Figure 5 is a fragmentary plan view of a split spinning ring.

In the drawing, the numeral 2 designates the ring rail of a spinning or twisting frame having a plurality of rings 3 mounted thereon. The spinning rings may be mounted directly in openings provided in the spinning rail itself for their reception, as illustrated, or, if desired, the rings may be mounted in openings in individual holders projecting from the ring rail and secured thereto by means of bolts or screws.

As shown more particularly in Figures 2 and 3, each ring 3 is provided with a traveler T which

moves about the ring and guides the yarn in the usual manner to a spool or bobbin, or the like take-up package, shown in dotted lines at 10 in Figure 1. Ring 3, which is preferably composed of a strong resilient material, and hence has a spring-like action, is non-continuous or split, the two ends 8 and 9 thereof being separated to form a gap through which the yarn or the like may be passed to the take-up package. The split ring 10 has an external, centrally disposed co-extensive flange 4. The ends 8 and 9 of the ring may normally tend to spring together, or may tend to spring apart.

In the embodiment of the invention shown in Figure 2, the ends 8 and 9 of the ring normally tend to spring apart and a means is provided for forcing the ends together to form a substantially continuous closed ring in use. As shown in Figure 2 such closing means takes the form of an eccentric 5 which is pivotally mounted on the ring rail as at 6 adjacent flange 4, as shown more clearly in Figure 1. The eccentric is provided with a handle 7 by means of which it can be swung against or away from the ring flange 25 to close or open the gap between the ends 8 and 9 of ring 3.

When it is desired to lace-up the spinning device, using the ring arrangement shown in Figure 2, the yarn is simply passed through the gap 30 in the ring, and threaded through the traveler. The eccentric 5 is pressed against the flange 4 of ring 3, forcing the two ends of the ring into engagement with one another, to form a closed circle, and the yarn is carried by the traveler 35 around the ring, and guided to the rotating take-up package in the usual manner. While the eccentric is maintained in that position, the ring remains closed. When it is desired to open the ring, the eccentric 5 is moved in the opposite direction, by manual manipulation of its handle 7, whereupon, the pressure exerted thereby on the ring flange is relieved, and the two ends of the ring immediately spring apart.

Referring now more particularly to Figures 3 and 4 the ends 8 and 9 of the ring shown therein normally tend to spring together, and a means is provided for opening the ring, as required. The means for forcing the ends 8 and 9 apart to provide a gap in the periphery of the ring takes the 50 form of an eccentric 11 having a handle 12 and pivotally mounted adjacent flange 4, as at 14. One end of a rigid strap 13 is pivotally secured to eccentric 11 by pin 15, and the other end thereof is pivotally secured to flange 4 of ring 3 by pin 16.

When it is desired to lace-up the spinning device, using the ring arrangement shown in Figure 3, eccentric 11 is moved away from ring 3, pulling strap 13, and hence flange 4 with it, thus forcing the ends 8 and 9 of ring 3 apart to form the desired gap therebetween. The yarn is passed through the gap and threaded through the traveler. Eccentric 11 is then moved in the opposite direction, toward ring 4, and the ends 8 and 9 are brought together again to form a substantially continuous closed circle.

The two ends of the split ring may be shaped to any complementary form which will enable them to fit together to form a smooth closure. In the ring illustrated in Figures 2 and 3 each end thereof has the approximate shape of a V, each V being disposed with its axis of symmetry horizontal and with their sides parallel, as shown at 1 and 8. Such a structure is entirely satisfactory because when pressure is exerted against the ring flange, the two V-shaped ends fit in to each other to form a smooth closure which does not interfere with continuous movement of the traveler about the periphery of the ring during the normal twisting and winding operation.

When a split spinning ring provided with means for optional closing or opening thereof, in accordance with my invention, is utilized in spinning and twisting yarns, thread, cord, or the like, by the ring and traveler system, the spinning device can be quickly and efficiently laced up, without requiring interruption of the rotation of the spindle carrying the take-up package and without causing inconvenience or delay to the operator of the spinning machine. The combination of a split spinning ring and means for closing or opening the same at will has the further distinct advantage that it may be readily adapted to the spinning and twisting of yarn of any desired yarn count.

Having thus described my invention and the advantages thereof, it will be apparent that variations may be made therein, and I do not wish to be limited to the exact details shown herein, except as set forth in the appended claims.

I claim:

1. In combination, a resilient split spinning ring, and means for varying the distance between the ends thereof.
2. In combination, a resilient split spinning ring the ends of which normally tend to spring apart to provide a gap in the periphery thereof, and means for forcing the ends of said ring together to form a substantially continuous closed circle.
3. In combination, a resilient split spinning ring the ends of which normally tend to spring apart to provide a gap in the periphery thereof, and pivotally mounted means adapted to be swung toward or away from said ring, to close or open the same.
4. In combination, a resilient split spinning ring the ends of which normally tend to spring apart to provide a gap in the periphery thereof, an external centrally disposed co-extensive flange on said split ring, and means pivotally mounted adjacent said flange for forcing the ends of said ring together to form a substantially closed circle.
5. In combination, a resilient split spinning ring the ends of which normally tend to spring apart to provide a gap in the periphery thereof, an external centrally disposed co-extensive flange on said split ring, and means pivotally

mounted adjacent said flange and adapted to be swung against or away from said flange, to optionally close or open said spinning ring.

5 6. In combination, a resilient split spinning ring the ends of which normally tend to spring apart to provide a gap in the periphery thereof, and an eccentric for forcing the ends of said ring together to form a substantially continuous closed circle.

10 7. In combination, a resilient split spinning ring the ends of which normally tend to spring apart to provide a gap in the periphery thereof, an external centrally disposed co-extensive flange on said split ring, and an eccentric pivotally mounted adjacent said flange and adapted to be swung thereagainst to force the ends of said ring together to form a substantially continuous closed circle.

15 8. In combination, a resilient split spinning ring the ends of which normally tend to spring apart to provide a gap in the periphery thereof, an external centrally disposed co-extensive flange on said split ring, and an eccentric pivotally mounted adjacent said flange and adapted to be swung against said flange or away therefrom, to optionally close or open the gap in said ring.

20 9. In combination, a resilient split spinning ring the ends of which normally tend to spring together, and means for forcing the ends of said ring apart to provide a gap in the periphery thereof.

25 10. In combination, a resilient split spinning ring the ends of which normally tend to spring together, and pivotally mounted means adapted to be swung away from said ring to force the ends apart to provide a gap in the periphery of the ring, or toward the ring to close the same.

30 11. In combination, a resilient split spinning ring the ends of which normally tend to spring together, an external centrally disposed co-extensive flange on said split ring, and means pivotally mounted adjacent said flange and associated therewith, for forcing the ends of said ring apart to provide a gap in the periphery thereof.

35 12. In combination, a resilient split spinning ring the ends of which normally tend to spring together, an external centrally disposed co-extensive flange on said split ring, and means pivotally mounted adjacent said flange and associated therewith adapted to be swung away from or toward said ring, to optionally open or close the latter.

40 13. In combination, a resilient split spinning ring the ends of which normally tend to spring together, and an eccentric for forcing the ends of said ring apart to provide a gap in the periphery thereof.

45 14. In combination, a resilient split spinning ring the ends of which normally tend to spring together, an external centrally disposed flange on said split ring, and an eccentric having means associated with said flange and adapted to be swung away from said ring to force the ends of the ring apart to provide a gap in the periphery thereof.

50 15. In combination, a resilient split spinning ring the ends of which normally tend to spring together, an external centrally disposed co-extensive flange on said split ring, and an eccentric pivotally mounted adjacent to and having means associated with the flange, said eccentric being adapted to be swung away from or toward said ring, to optionally open or close the same.
